US0D1095336S

(12) **United States Design Patent** (10) **Patent No.:** **US D1,095,336 S**
(45) **Date of Patent:** ** Sep. 30, 2025

(54) **AUTOMOBILE**

(71) Applicant: **Zhejiang Leapmotor Technology Co., Ltd**, Hangzhou (CN)

(72) Inventors: **Zifeng Yu**, Zhejiang (CN); **Shaoming Wang**, Zhejiang (CN); **Weiwei Gao**, Zhejiang (CN); **Pengcheng Zhou**, Zhejiang (CN); **Doudou Zhang**, Zhejiang (CN); **Tiwei Lu**, Zhejiang (CN); **Yiqun Wu**, Zhejiang (CN); **Wentao Li**, Zhejiang (CN); **Wenyou Yan**, Zhejiang (CN); **Xingchen Lei**, Zhejiang (CN); **Boyi Ni**, Zhejiang (CN); **Wei Zhou**, Zhejiang (CN); **Jianing Wu**, Zhejiang (CN); **Shuyue Yu**, Zhejiang (CN); **Song Zhang**, Zhejiang (CN); **Mingxiao Zheng**, Zhejiang (CN)

(**) Term: **15 Years**

(21) Appl. No.: **35/518,828**

(22) Filed: **Sep. 8, 2023**
